UNITED STATES PATENT OFFICE.

WEARD SCHOON, OF STEEN, MINNESOTA.

HUMIDIFIER.

Application filed March 14, 1925. Serial No. 15,685.

This invention relates to improvements in humidifiers for use in connection with internal combustion engines and has for its principal object to provide a simple and efficient device for supplying moistened air to the carbureter whereby the efficiency of the operation of the internal combustion engine is increased and also reducing the consumption of fuel.

10 A still further object is to provide a humidifier of the above mentioned character which will operate automatically, thus insuring the supply of a proper amount of moistened air to the carbureter, means being provided for preventing any possibility of water entering the carbureter.

20 A still further object is to provide a humidifier of the above mentioned character which may be readily and easily attached with the several parts of an automobile with which the device is associated without necessitating any material alterations of said parts.

25 A still further object is to provide a humidifier of the above mentioned character which will at all times be positive and efficient in its operation, which is further simple in construction, inexpensive, and furthermore adapted to the purposes for which 30 the same is designated.

Other objects and advantages of this invention will become apparent during the course of the following description.

35 In the accompanying drawing forming a part of this specification, and in which like numerals are employed to designate like parts throughout the same:

40 Figure 1 is an elevational view of the humidifier embodying my invention showing the same connected up for use with an internal combustion engine.

45 Fig. 2 is an enlarged elevational view of the casing with parts broken away and illustrating the valve arranged in the casing, and

50 Fig. 3 is a transverse section taken approximately on the line 3—3 of Fig. 2.

55 In the drawing wherein for the purpose of illustration is shown the preferred embodiment of my invention, the numeral 1 designates a substantially cylindrical casing, the same being provided with an apertured ear 2 at its top for attaching the casing to the core of the radiator 3 of an automobile on the inside thereof as clearly illustrated in Fig. 1.

An overflow pipe 4 extends from the top of the radiator into the top of the cylindrical casing 1 so that the moistened air and steam generated in the top of the radiator will be discharged into the casing. A steam outlet 60 pipe 5 communicates at one end with the casing 1 at a point adjacent the top thereof through the medium of a suitable fitting illustrated at 6. The opposite end of the pipe 5 communicates with the air intake of the 65 carbureter 7 of the internal combustion engine generally designated by the numeral 8.

A water outlet pipe 9 extends downwardly from the bottom of the casing, the same having communication therewith through the 70 medium of a fitting 10. Arranged within the casing 1 at the lower portion thereof is the horizontally extending plate or disk 11, the same being provided with an opening 12. A flap valve 13 fashioned from the punch- 75 ing of plate 11 to form the opening 12 normally closes the opening 12 and this valve is pivotally supported on the plate or disk 11 as illustrated at 14. An axle coiled spring 15 is associated with the pivot pin 14 and 80 provides a means for normally holding the valve 13 in its closed position. The purpose of the valve will be certainly apparent.

With the parts arranged as shown in Fig. 1, the vapor formed in the top of the radiator 85 will enter the pipe 4 and will flow into the cylindrical casing 1. A quantity of moistened air and steam will be supplied to the internal combustion engine 8 by the pipe 5, it being understood of course that the 90 amount of moistened air which is admitted to the carbureter of the internal combustion engine will be controlled by the opening of the throttle, so that when the throttle is open, a large amount of moistened air will be supplied to the internal combustion engine and as the throttle is gradually closed, the supply of moistened air to the carbureter is 95 gradually decreased.

In order to prevent any possibility of the 100 water which may overflow from the radiator and enter the casing 1 through the pipe 4, being admitted to the carbureter, the valve 13 will open under the weight of the water so that the water will flow outwardly from 105 the casing 1 through the outlet pipe 9. The valve 13 will automatically return to its closed position when all of the water has been discharged from the casing so that the moistened air and steam will not escape 110

out through the pipe 9, thus assuring the supplying of the moistened air to the carbureter through the pipe 5.

A humidifier of the above mentioned character will at all times be positive and efficient in carrying out the purpose for which it is designated and the simplicity in which the device is constructed enables the same to be readily and easily installed upon an automobile and will not in any way interfere with the usual operation thereof.

By admitting a supply of moistened air to the carbureter, the consumption of fuel will be reduced to a minimum and furthermore 15 the collection of carbon also be minimized.

While I have shown the preferred embodiment of my invention, it is to be understood that various changes in the size, shape, and arrangement of parts may be resorted 20 to without departing from the spirit or scope of the appended claim.

Having thus described my invention, what I claim as new is:—

A humidifier for an internal combustion 25 engine, comprising a cylindrical casing, a steam inlet pipe extending into the closed upper end of the casing, a plate arranged horizontally in the lower portion of the cas-

ing, whereby the latter is divided into a relatively large upper moistened air compartment, and a relatively small water compartment in the lower portion of the casing, a moistened air discharge pipe extending from the side of the upper portion of the moistened air compartment, a water discharge 35 pipe extending from the closed lower end of the cylinder and communicating with the water compartment, said plate being provided with an enlarged central opening by punching out the central portion thereof, a flap valve fashioned from said punched out portion pivotally associated with the plate and cooperating with the opening, resilient means for normally holding the valve in a closed position, said flap valve adapted to be 40 actuated by the weight of the water entering the casing from the steam inlet pipe to permit the water to be discharged from the moistened air compartment into the water compartment, and out through the water discharge pipe, the flap valve normally preventing the moistened air from entering the water compartment.

In testimony whereof I affix my signature.

WEARD SCHOON.
